E. G. GARTIN

TOOL RETAINER

Filed Dec. 15. 1922

Patented Sept. 11, 1928.

1,684,177

UNITED STATES PATENT OFFICE.

ELMER G. GAETIN, OF CLAREMONT, NEW HAMPSHIRE, ASSIGNOR TO SULLIVAN MACHINERY COMPANY, A CORPORATION OF MASSACHUSETTS.

TOOL RETAINER.

Application filed December 15, 1922. Serial No. 607,036.

My invention relates to tool retainers. An object of my invention is to provide an improved tool retainer. Another object of my invention is to provide an improved retainer for rock drilling devices in which the tool retainer may be conveniently positioned by the means used for holding the tool assembled. These and other objects and advantages of my invention will hereinafter be 10 more fully apparent.

In the accompanying drawings I have shown for purposes of illustration one embodiment which my invention may assume in practice.

15 In these drawings,—

Fig. 1 is a view partially in elevation and partially in section showing the front end of a drilling tool provided with the illustrative embodiment of my improved tool retaining means.

20 Fig. 2 is a view taken at right angles to Fig. 1 and showing parts broken away to disclose details of construction, the retainer being shown in operating position in full lines and in inoperative position in dotted lines.

25 In the illustrative embodiment of my invention I have shown the same arranged upon a percussive motor 1 whose chuck housing and front head enclosing portion is indicated at 2.

30 The member 2 is provided at opposite sides with lugs or abutments 3 through which bores 4 extend; and through these bores the side rods 5 which serve to hold the parts of the tool in assembled relation are passed. At the front portion of the lugs 4 arcuate seats 6 are milled and in these seats there are arranged similarly curved projections or bosses 7 which serve as journal members for a tool 35 retainer yoke 8 to which they are herein integrally secured. The members 7 are traversed by openings 9 which are of greater area at their extremities than at their central portions. The members 7 are journaled upon 40 the arcuate surfaces 6 and around them at either side passes a yoke member 10 which is bored at 11 to permit the side rods to pass through the same, the legs 10^a of these yoke members abutting against the lugs 3. Fol-

45 lower members 12 also bored to permit the side rods to pass therethrough and having arcuate surfaces 13 opposite the arcuate surfaces 6 surround each of the side rods and are disposed between the legs 10^a of the yokes 10. In assembling the device, assume that

the side rods and the members 1 and 2 are in assembled position. The yoke 8 is then placed in position by passing the openings 9 traversing the bosses 7 over the side rods 5. The followers 12 are next slid over the side 60 rods. Relatively light but strong springs 14 are next slid over the side rods. These are followed by the yokes 10. Thereafter considerably heavier springs 15 are slid into position on the side rods and finally nuts 16 are 65 put on and tightened up at the ends of the side rods. After the ends of the legs 10^a of the yokes have engaged the abutments 3, further tightening of the nuts 16 cannot increase the tension of the springs 14. Hence further 70 adjustment of the nuts 16 will allow the rods 5 to be brought to any desired tension without influencing operation of the tool retainer in the least. It will be noted that at the sides of the front of the chuck housing member 75 2 there are notches cut away as at 17 into which the side elements 18 of the retainer member 8 may snap to hold the same in tool retaining position.

From the foregoing description the mode 80 of operation of my improved tool retaining means will be readily apparent. When it is desired to insert a tool in position, the retainer yoke 8 will be moved from the position shown in full lines in Fig. 2 to that indicated 85 in dotted lines, this swing being possible by reason of the shape of the openings 9. When it is desired to hold a steel in position during retraction from the hole, the retainer will be snapped down from the dotted to the full 90 line position and by the engagement in the recesses 17 of the side elements 18 of the retainer yoke 8, the parts will be held in tool retaining position. It will be observed that resilience is provided both by the shape of the 95 retainer yoke 8 and more particularly by the light but strong spring 14 which may be compressed during forward movement of the retainer and which will on removal of strain at once return the retainer to longitudinal 100 position. It will be noted moreover that this yielding mounting of the retainer is accomplished without sacrificing the strong but still not rigid assembly of the parts, the heavier spring 15 acting upon the yoke 10 to 105 hold the parts of the drilling mechanism securely but not rigidly assembled though the retainer move relative to the drill.

While I have in this application specifically described one form which my invention may 110

assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a tool retainer, a pair of tension members adapted to hold the parts of a drill assembled, a retainer yoke pivoted on said members, springs surrounding said members and adapted when placed in compression to hold said retainer member in position, a yoke extending on opposite sides of said springs and also carried on said members, heavier springs overlying said members, and means for placing said springs under compression.
2. In a tool retainer mechanism, tension members adapted when under tension to hold the parts of a motor in assembled relation, a tool retainer guided on said members, resilient means coacting with said tool retainer member, a stronger resilient means placed under compression to place said members and resilient means under tension, and stationary means for preventing said second mentioned resilient means from compressing said first mentioned resilient means beyond a predetermined limit.
3. In a drilling mechanism, a member having a pair of lugs formed thereon, rods passing through said lugs, yokes on each of said rods having legs engaging said lugs and providing a free space between their legs, means cooperating with said rods for holding said yokes against said lugs, and tool retaining means having portions resiliently located in said spaces.
4. In a drilling mechanism, a member having a pair of lugs formed thereon, rods passing through said lugs, yokes on each of said rods having legs engaging said lugs and providing a free space between their legs, means cooperating with said rods for resiliently holding said yokes against said lugs, and tool retaining means having portions resiliently located in said spaces.
5. In a drilling mechanism, a member having a pair of lugs formed thereon, rods passing through said lugs, yokes on each of said rods having legs engaging said lugs and providing a free space between their legs, means cooperating with said rods for resiliently holding said yokes against said lugs, pivoted tool retaining means having portions resiliently located in said spaces, and means for releasably holding said tool retaining means in tool engaging position.
6. In a drilling mechanism, a pair of members adapted when under tension to hold the parts of the drilling mechanism assembled, lugs through which each of said members pass, a nut on each of said members, a tool retainer yoke pivoted on said members between

said lugs and nuts, yokes on each of said members surrounding the pivot portions of said retainer yoke, and springs on opposite sides of said second-mentioned yokes.

7. In a drilling mechanism, a pair of members adapted when under tension to hold the parts of the drilling mechanism assembled, lugs through which each of said members pass, a nut on each of said members, a tool retainer yoke pivoted on said members between said lugs and nuts, yokes on each of said members surrounding the pivot portions of said retainer yoke, and springs of different strength on opposite sides of said second-mentioned yokes. 80

8. In a drilling mechanism, a pair of members adapted when under tension to hold the parts of the drilling mechanism assembled, lugs through which each of said members pass, a nut on each of said members, a tool retainer yoke pivoted on said members between said lugs and nuts, yokes on each of said members surrounding the pivot portions of said retainer yoke, and springs of different strength on opposite sides of said second-mentioned yokes, the compression of certain of said springs being determined by the length of said second mentioned yokes. 90

9. A drilling mechanism comprising a plurality of parts, means for resiliently holding said parts together including tension elements and resilient means for subjecting them to tension, tool retaining means, resilient positioning means for said retaining means, means for tensioning said holding means and compressing said resilient positioning means, and fixed means for limiting the initial compression of said resilient means independently of further tensioning of said holding means. 100

10. A drilling mechanism comprising a plurality of members, resilient means for holding said members together including a plurality of tensioned side rods and resilient means associated therewith, tool retaining means, resilient positioning means therefor, means for tensioning said rods and compressing said resilient positioning means, and fixed means for limiting the initial compression of said resilient means independently of further tensioning of said rods. 105

11. A drilling mechanism comprising a plurality of members, resilient means for holding said members together including a plurality of tensioned side rods and springs for tensioning said rods, tool retaining means having portions engaging said rods, resilient positioning means therefor, said rod-engaging portions of said retaining means and resilient means being disposed within the longitudinal tensioned limits of said rods, means for tensioning said rods and compressing said resilient positioning means, and means for limiting the initial compression of said resilient means independently of further tensioning of said rods. 120

130

12. In a drilling mechanism, tool retaining means therefor, means including tensioned rods for connecting said means to said mechanism, said retaining means having portions engaging said rods, resilient positioning means for said tool retaining means, said resilient means and said rod-engaging portions of said retaining means being disposed within the longitudinal tensioned limits of said rods, means including springs for tensioning said rods and compressing said resilient means, and fixed means for limiting the initial compression of said resilient means independently of further tensioning of said rods.
13. In a drilling mechanism, tool retaining means therefor, means including resilient means and side rods for resiliently holding the parts of said drilling mechanism together, resilient positioning means for said retaining means, means for simultaneously tensioning 20 said rods and compressing said resilient positioning means, and fixed means for limiting the initial compression of said resilient means independently of further tensioning of said rods. 25

In testimony whereof I affix my signature.

ELMER G. GARTIN.
